UNITED STATES PATENT OFFICE

EDGAR B. NICHOLS, OF CAMDEN, NEW JERSEY, ASSIGNOR TO THE PFAUDLER CO., OF ROCHESTER, NEW YORK, A CORPORATION OF NEW YORK

LIQUID-PROCESSING APPARATUS

Application filed January 27, 1928. Serial No. 250,048.

The present invention relates to a liquid processing apparatus of the heat exchange type and has for its object to provide improved means of this class designed particularly for use in the treating of liquids such, for example, as employed in the processing of foods and other substances by heating or cooling treatment.

A further object of the invention is to provide improved conducting means for a heating or cooling medium in conjunction with a container for the liquid to be treated or processed, designed in such a manner as to regulate the supply of the medium and to permit the heating or cooling surface to be increased or decreased as desired in accordance with the amount or nature of the liquid to be processed.

A further object of the invention is to provide an improved arrangement of heating or cooling sections or coils designed for conveniently regulating the extent of the effective surface of the coils by individual control thereover whereby to more effectively and economically treat the liquids to be processed.

A still further object of the invention is to provide an improved heat exchange system embodying coils or tubular sections designed in a manner to permit a series of the same to be readily assembled and individually controlled in order to effect regulation of the flow of the heating or cooling medium to one or more of the coils or sections without effecting the supply of the heat exchange medium to the remaining coils, the several coils having automatic pressure responsive means for regulating the flow of the heating medium therethrough and the coils being so constructed as to permit additional coils to be readily added or replacements made from time to time with but little inconvenience.

To these and other ends the invention resides in certain improvements and combinations of parts, all as will be hereinafter more fully described, the novel features being pointed out in the claims at the end of the specification.

In the drawings: Fig. 1 is a part sectional elevation of an ap-

paratus embodying one form of the invention;

Fig. 2 is a sectional plan through the tank showing the arrangement of the coils therein;

Fig. 3 is an enlarged sectional elevation 55 through the coil sections taken on line 3^a—3^a of Fig. 2;

Fig. 4 is an enlarged detail sectional plan taken on line 4^a—4^a of Fig. 3;

Fig. 5 is a sectional plan taken on line 5^a—5^a of Fig. 3.

Similar reference numerals throughout the several views indicate the same parts.

In the manufacturing or processing of food products, as for example, the pasteurizing of 65 milk or the treating of other liquids, it is essential to have a series of conducting units for the heat exchange medium to be used designed so as to permit of the employment of varying quantities of the medium as may be required for different quantities of the liquids to be processed or treated from time to time. In other words, the area of the heating or cooling surface should be proportional to the quantity of liquid to be treated 75 and in the present invention the coils have been so designed that they may be independently controlled for this purpose or the quantity of the heating or cooling medium supplied to each varied as desired.

Furthermore, the coils at the points where they discharge one into another are provided with automatic pressure operated valves which open and close according to the variations in pressure on the opposite sides thereof, but which are arranged to prevent back-flow of the steam or other medium from a receiving coil to the coil discharging thereto, or from a lower to an upper coil when the pressure in the former is greater than in the latter.

The coils are so constructed that they may be readily assembled within the tank by building up or superimposing one section upon another and the arrangement shown 95 is such that the sections, in case of repairs, may be quickly removed with but little interruption in the use of the apparatus and with comparatively small expense.

In the arrangement shown in Figs. 1 to 5 100

inclusive, three complete coils are provided, but it will be understood that this number may be increased if desired and that their location within the tank may be varied to a certain extent. The coils are each formed of oppositely extending sections located in planes one above another and having heads at their opposite ends in superimposed relation as shown in Fig. 3. Furthermore, the 10 inlet head of each section is preferably elevated with respect to the opposite or outlet head of the section to insure proper drainage of the heating or cooling medium from each section to the next adjacent section there- 15 beneath. Also, the upper and lower heads of each coil at the left or inlet side thereof, as viewed in Fig. 3, are in constant communication so that the steam or fluid when entering the coil will flow in opposite direc- 20 tions to the lower heads at the opposite ends of the sections which are also in communication. However, the bottom wall of the outlet head of each lower section of a given coil is adapted to form a closure for the head 25 of the upper section of the next succeeding coil therebeneath as indicated at the right of Fig. 3, and said wall forms a support for the pressure operated check valve provided for controlling the flow of the steam or liquid 30 from one coil to another.

Referring to the drawings, 10 represents a tank or container of any suitable form, which is adapted to be supported in any desired manner and which is provided with a 35 curved bottom 11 as indicated in Fig. 1. The tank is provided with suitable inlet and outlet openings not shown for the milk or other liquid to be treated and is preferably provided interiorly with a suitable coating of 40 enamel for protecting the foods or other products to be treated therein.

The lowermost coil comprises an upper section 12 and a lower section 13, the former having a head 12^a provided with a fluid inlet connection 14 which may be cast integral with the head or detachably connected therewith in any suitable manner. The lower or opposite head of section 12 is indicated at 45 15 and is superimposed upon the outlet head 50 16 of the lower section 13 while the inlet head 12^a of the upper section is superimposed upon and in communication with the head 17 of the lower section. The outlet head 16 is preferably provided with an extension 16^a with 55 15 which is connected a discharge pipe 18 inclined downwardly as shown in Fig. 1 and having an elbow 19 thereon communicating with a flanged head 20 supported by the bottom 11 of the tank and having a discharge 60 15 pipe 21 leading therefrom. The pipe 21 may be suitably connected with a tank or container not shown for receiving the exhaust steam or liquid from the coils when discharged 65 15 therefrom.

66. The second coil from the bottom Fig. 1

comprises the upper and lower sections 22 and 23 respectively, the former having inlet and outlet heads 24 and 25 superimposed upon the corresponding heads 26 and 27 of the lower section. Likewise the uppermost 70 coil comprises upper and lower sections 28 and 29 respectively, the former having inlet and outlet heads 30 and 31 superimposed upon the corresponding heads 32 and 33 of section 29. The heads 24 and 30 like the head 12^a are provided with suitable inlet connections 34 and 35 respectively as indicated in Fig. 1. The inlet connections take into heads 36 suitably secured upon the wall of the tank as shown in Fig. 1 and pipes lead from said heads having valves 37 for regulating the supply of steam or liquid to each coil or for cutting off the supply to any one of the coils or to all of the same as may be required under different conditions of operation.

The heads 17 and 30 of the sections 13 and 28 are preferably provided with closures 17^a and 30^a respectively which are clamped upon the heads preferably by a tie rod 39 for clamping the sections together, the tie rod having a nut on its upper end and being threaded at its lower end into a boss on the closure 17^a. A similar clamping bolt 39 serves to connect the opposite ends of the sections at the outlet ends thereof, said bolt being extended through a closure 31^a for the head 31 and having its lower end threaded into a boss on the head 16 of the lowermost section 13.

It will be noted from Fig. 3 that the heads 32 and 26 are provided with lower walls 40 which serve to close openings in the heads 24 and 13 respectively. Likewise, the heads 33 and 27 at the right of Fig. 3 are provided with walls 41 which serve to close openings in the heads 25 and 15 respectively. The heads of the upper section of each coil have openings at both sides to facilitate casting of the sections and the walls 40 and 41 serve to close the upper openings in the heads of sections 22 and 12 as indicated in Fig. 3. Thus each coil comprises an independent circulating unit arranged to discharge into the outlet end of the upper section of the next succeeding coil therebeneath.

The walls 41 of heads 33 and 27 are provided with relatively small discharge openings 42 arranged to be closed by check valves 43 at the lower sides thereof which are slidably mounted on studs 44 depending from side walls and having relatively light springs 45 coiled about the same and serving to normally seat the valves but permitting them to open and close under varying pressures on opposite sides thereof. The valves, however, are provided for preventing discharge of the steam upwardly from one coil into another should the pressure become greater in a lower than in the next adjacent upper coil. It will be understood, however, that since the steam

or liquid in the lowermost sections 12 and 13 has a free and unrestricted outlet, the pressure therein will be somewhat lower than in the sections of the coil thereabove where the pressure tends to build up when the valves become seated. Likewise, the pressure in the intermediate coil will be slightly lower than in the uppermost coil so that the upper valve will freely open to permit the downward discharge of the heating medium therethrough. In this way proper circulation of the heating medium is assured at all times.

I claim as my invention:

1. In a fluid circulating system, a series of superimposed coils comprising oppositely extending upper and lower communicating sections inclined to the horizontal and arranged to circulate fluid in opposite directions from the high to the low points of the coils, said coils having communicating passages at said low points for the passage of all the fluid from each upper coil to the next succeeding coil therebeneath, a supply connection leading to the upper end of one section of each coil and means arranged to secure said coils one upon another.

2. In a fluid circulating system, a series of superimposed coils comprising oppositely extending upper and lower sections having communicating heads at their opposite ends, the upper heads of the different coils being non-communicating and the lower head of the bottom section of each coil being in communication with that of the top section of the coil next beneath the same and a separate fluid supply connection leading to one upper head of each coil.

3. In a fluid circulating system, a series of superimposed coils comprising oppositely extending upper and lower sections having communicating heads at their opposite ends, the sections being inclined to the horizontal whereby to raise their heads one above another, the coils at the lower ends of the sections being in communication one with another and non-communicating at the upper ends of the sections, separate fluid supply pipes leading to the upper sections of the coils adjacent their raised ends, individual valves for said supply pipes permitting the supply to the different coils to be cut off or regulated at will and means for securing the sections one upon another.

4. In a fluid circulating system, a series of superimposed coils each formed of a plurality of pipe sections having oppositely disposed communicating inlet and outlet heads arranged one above another, each coil having a separate fluid supply connection leading to one of the inlet heads thereof and having a discharge passage leading from one outlet head to the next succeeding coil therebeneath, the inlet heads of the several coils being non-communicating, and means serving to secure said coils one upon another.

5. In a fluid circulating system, a series of superimposed coils formed of a plurality of oppositely extending communicating sections located one above another and each arranged to circulate the fluid in opposite directions from the junction point of the sections, each coil having a discharge passage communicating with the next succeeding coil therebeneath at a point opposite said junction point, an independent fluid supply connection leading to each coil adjacent said junction point, all of the fluid entering each connection circulating through the coil corresponding thereto and means serving to connect said coils.

6. In a fluid circulating system, a series of superimposed coils comprising oppositely extending upper and lower sections having communicating heads at their opposite ends, the lower heads of one coil being disposed upon the upper heads of the next succeeding coil therebeneath, the heads of all of the sections at one end being in communication, said coils being non-communicating at the opposite ends of the sections, a separate fluid supply connection for each coil leading to the non-communicating ends of the sections and means serving to secure said coils one upon another.

7. In a fluid circulating system, a plurality of pipe sections assembled to extend alternately in opposite directions and having heads at their opposite ends in superimposed relation whereby to afford a series of coils arranged one above another, said coils having their heads elevated at one side above the heads at the opposite side and having separate fluid supply connections leading to the elevated heads, the lower sections of the several coils each having a discharge passage leading to the upper section of the next succeeding coil therebeneath, the elevated heads of the several coils being non-communicating, and means for securing said sections one upon another.

8. In a fluid circulating system, a plurality of pipe sections assembled to extend alternately in opposite directions and having inlet and outlet heads at their opposite ends in super-imposed relation, the heads of each alternate section having openings in one side thereof and the heads of the next adjacent section serving to close said openings the outlet heads being in communication and the inlet heads of the different sections being non-communicating and means serving to secure said sections one upon another.

9. In a fluid circulating pressure system, a series of superimposed coils comprising oppositely extending upper and lower sections having inlet and outlet heads, the outlet heads of the several coils having passages therebetween to permit the downward discharge of fluid from one coil to another and the inlet heads of the different coils being non-communicating, valves for automatically check-

ing the flow of fluid through said passages from a lower to an upper coil when the pressure in the former is greater than in the latter, a supply connection leading to each coil and means for securing said coils one upon another.

10. In a fluid circulating pressure system, a series of superimposed coils supported one by another and comprising oppositely extending upper and lower sections inclined to the horizontal, the lower sections of the coils having passages leading to the upper sections of the next succeeding coils therebeneath, valves for automatically checking the flow of fluid through said passages from a lower to an upper coil when the pressure in the former is greater than in the latter, separate supply connections leading to said coils and means serving to secure the sections one upon another.

15. 11. In a fluid circulating system, a series of coils each comprising oppositely extending upper and lower sections having fluid inlet and outlet heads at their opposite ends in communication one with another, the heads of the lower section of one coil forming closures for openings in the heads of the next succeeding section therebeneath, valves for the outlet heads of the lower coil sections arranged to automatically check the flow thereto of fluid from the outlet head of the section next beneath the same when the pressure in the latter is greater than in the former, and a separate supply pipe for one section of each coil.

20. 12. In a fluid circulating system, a series of coils each comprising oppositely extending pipe sections having inlet and outlet heads at their opposite ends, one outlet head of each coil having an opening leading to the outlet head of the coil next adjacent thereto, a valve for said opening arranged in the last mentioned head and adapted to check the flow of fluid therefrom to the next adjacent outlet head when the pressure in the former is greater than in the latter, a separate supply connection leading to each inlet head and means serving to secure said sections one upon another.

25. 13. In a fluid circulating system, a plurality of superimposed fluid circulating coils, each comprising a pair of pipe sections extending in opposite directions and communicating one with another, pressure controlled valves between said coils for checking the back flow of the fluid from a lower to an upper coil when the pressure is greater in the former than in the latter and permitting discharge of the fluid from the upper to the lower coils when the pressure in said lower coils is reduced below that in the upper coils, separate fluid supply connections leading to said coils, a separate valve for each of said connections and means serving to secure said coils one upon another.

30. 14. In a heat exchange apparatus, a tank for holding a liquid to be treated, a fluid circulating system disposed within the tank comprising a series of coils each formed of a plurality of pipe sections having oppositely arranged communicating inlet and outlet heads disposed one upon another, the inlet heads of the several coils being non-communicating and the outlet heads being in communication one with another, separate fluid supply conduits leading through the tank wall to the inlet heads of said coils and a discharge conduit leading from the tank and connected with the outlet head of one of the coils.

35. 15. In a fluid circulating pressure system, a series of superimposed coils having outlet heads arranged to discharge one into another, said heads having pressure responsive valves for checking the back flow of the fluid from a lower to an upper head when the pressure in the former is greater than in the latter and individual supply conduits leading to each of the coils.

40. 16. In a fluid circulating system, a plurality of tubular sections having superimposed inlet and outlet heads the latter discharging one into another and the former being non-communicating, a discharge pipe leading from one of the outlet heads, individual supply pipes leading to the inlet heads and valves for regulating the supply of fluid delivered by said individual pipes.

45. 17. In a liquid processing apparatus, a container for holding a liquid to be treated, a fluid pressure circulating system within the container for treating the liquid comprising a plurality of tubular sections having superimposed outlet heads arranged to discharge one into another, certain of said heads having pressure responsive valves for checking the back flow of the fluid therefrom when the pressure therein becomes greater than that in the head discharging thereto and means for conveying fluid under pressure to said tubular sections.

50. 18. In a liquid processing apparatus, a container for holding a liquid to be treated, a fluid pressure circulating system within the container for treating the liquid comprising a plurality of tubular sections having superimposed outlet heads arranged to discharge one into another, individual supply conduits leading through the wall of the container to said tubular sections, valves interposed in said conduits for individually regulating the supply of fluid to said tubular sections and a discharge conduit leading from the container and connecting with the outlet head of one of said sections.

55. 19. In a liquid processing apparatus, a container for holding a liquid to be treated, a fluid pressure circulating system within the container for treating the liquid comprising a plurality of tubular sections having superimposed inlet heads and superimposed outlet

heads the latter being arranged to discharge one into another, certain of said outlet heads having pressure responsive valves for checking the back flow of the fluid therefrom when the pressure therein becomes greater than that in the head discharging thereto and individual fluid supply conduits leading to said inlet heads and having valves for regulating the fluid supply.

20. In a processing apparatus, the combination with a container for holding materials to be processed, of a plurality of conduit sections within said container for holding treating fluid, inlet means for supplying fluid to each of said conduit sections individually, discharge conduit means leading from one of said conduit sections, and means providing a passage for discharge flow from each of the other conduit sections to the conduit section from which said discharge conduit means leads.

21. In a processing apparatus, the combination with a container for holding material to be processed, of a plurality of conduit sections within said container for holding treating fluid, inlet means for supplying fluid to each of said conduit sections individually, discharge conduit means leading from one of said conduit sections, means providing a passage for discharge flow from each of the other conduit sections to the conduit section from which said discharge conduit means leads, and check valve mechanism preventing reverse flow from said last named conduit section to any of the other conduit sections.
